ADJUSTABLE EARPIECE SUPPORT

George H. White, Hartford, Conn., assignor to
 The Gray Manufacturing Company, a corpora-
 tion of Connecticut

Application June 5, 1947, Serial No. 752,778

9 Claims. (Cl. 179—182)

1

The manner of supporting body supported receivers of both acoustical and electrical types has failed to keep pace with the developments in the several arts in which they are used. From the early days of telegraphy and telephony there have been continued efforts to improve such devices for use in the fields of radio, hearing aids, transcription and communication generally, but thus far nothing has been proposed which is satisfactory from the standpoints of light weight, ease of application and removal, permitting freedom of movement by the wearer, comfort in use for sustained periods, and adjustability to accommodate differences in ear structures.

Head bands, ear plugs, helmets, and supports for attachment to the pinna and other portions of the body have been disclosed in the patented art and produced commercially, but all of them have been subject to one or more of the disadvantages of excessive weight, general discomfort, irritation to the skin, restriction of movement, and inconvenience in their application and removal.

As a matter of fact, such objections to earpieces of the types heretofore available have accounted for appreciable resistance to the adoption of office transcribing equipment. The typical secretary almost without exception objects to the use of a head band for supporting an earpiece because of its appearance, because it is uncomfortable to wear and because it spoils the appearance of her coiffure. Devices that plug into one or both ears are irritating to the skin, reduce the fidelity of the sound produced and for other reasons have failed from the standpoint of universal acceptability. Various constructions intended to be supported from the pinna of the ear have been proposed, but they have not possessed the degree of adjustability, comfort and convenience required for their adoption to any appreciable extent.

The present invention seeks to overcome the many disadvantages inherent to devices previously proposed for this purpose by providing an earpiece comprising a plurality of pivotally articulated members adjustably related for engagement of opposite surfaces of the pinna of the human ear, one of the members providing means for attachment of a sound source. It is proposed that there be two such pivotally articulated members, one of which may have a curved surface substantially complementing a posterior portion of an average pinna. The articulation of the members will preferably occur forwardly of the pinna and the member providing means for attachment of

the sound source will preferably support such sound source adjacent the concha of the human ear. It is also proposed that yieldable means be provided for maintaining the members in an adjusted relationship with respect to one another during ordinary operating conditions. The articulated members may be relatively offset and the sound source supported thereby may be of a sound translating type, which may itself be 5 adjustably mounted on one of the members. The adjustability of the sound translating device may include rotation, and it may be resiliently mounted with respect to one of the articulated members. It is contemplated that at least one 10 of the articulated members be yieldable so as to adjustably mount the sound source. The sound translating device may be resiliently mounted with respect to one of the articulated members. It is contemplated that at least one of the articulated members be yieldable so as to 15 partially compensate for variations in sizes and shapes of various ears. The sound translating device is preferably mounted externally on one of the members for assuming an operative position spaced from the pinna for reasons involving both acoustics and comfort. One of the articulated members preferably possesses a depending end providing means for attachment of the sound source, this end having an operative position 20 overlying the concha of the average human ear. One of the articulated members is provided with portions for engaging above and behind the pinna of the human ear. It is advantageous that at least one of the articulated members be resilient, and under many circumstances it is preferable 25 that the members have substantially coplanar portions, in which case they may likewise possess offset portions. It is particularly advantageous 30 where the earpiece is to be used optionally with the right or left ear that the member to which the sound source is to be attached have opposed surfaces each providing means for such attachment. Under these circumstances, it is contemplated 35 that a recessed resilient ring be carried by one of the members providing yieldable means for attachment and detachment of the sound source.

40 A more complete understanding of the present invention will follow from a description of the attached drawing wherein:

Fig. 1 is a perspective view of one contemplated form of the earpiece supporting an electrical sound translating device;

Fig. 2 is an elevation showing the earpiece with the sound translating device removed, in position on a human ear;

Fig. 3 is an elevation showing the remote surfaces of the device depicted in Fig. 1;

2

Fig. 4 is a fragmentary section taken along line 4—4 of Fig. 3;

Fig. 5 is an elevation taken from the left end of the device depicted in Fig. 3;

Fig. 6 is a view corresponding to Fig. 3 of a modification;

Fig. 7 is a fragmentary section taken along line 7—7 of Fig. 6;

Fig. 8 is an elevation of the left end of the device depicted in Fig. 6 showing a sound translating device as applicable to either surface; and

Fig. 9 is a plan view of the earpiece depicted in Fig. 6.

The earpiece depicted in Figs. 1 to 5 inclusive comprises a supporting member 20 adapted to be positioned posteriorly with respect to the pinna 22 of a human ear depicted in Fig. 2; the member having a curved edge 24 of a formation contemplated to complement the junction of the average ear with the head. A depending member 26 is pivotally articulated at its upper end to the forward end of the supporting member 20 by means of a rivet 28 or the like, with suitable bearing means such as washers 30 interposed between the members. A spring washer 32 is interposed between one end of the rivet and a proximate surface of one of the members so that any adjusted position imparted to the members will be retained, undisturbed by forces to which the device might be subjected in normal use. At the same time, the resilient washer 32 will permit the members to move relatively without injury to the ear of the wearer should any unusual forces be encountered during the use of the device. An electrical sound translating device 34 has been shown as mounted on the depending member 26 in Fig. 1, having a pair of conductors 36 extending therefrom for connection with a source of energy from which the sound is to be translated.

The sound translating device has been removed from the earpiece as depicted in Fig. 2 to clarify the relationship attained with respect to the concha 33 of the ear. A mounting ring 40 is secured to the depending end of the member 26 in a position that will approximately overlie the concha, the ring being suitably attached thereto by molding, friction, or otherwise, and preferably being coplanar with the surfaces of the member itself. As will be apparent from Fig. 4, the ring 40 is provided with an inner peripheral groove 42 to receive a resilient annulus 44 having a normal internal diameter less than that of the ring 40 to serve as a snap fastener to receive a grooved nipple 46 projecting from the translating device 34. Thus it will follow, that the sound translating device can be attached and detached with respect to the depending member 26 by merely snapping it to or from its operative relationship, and due to the nature of the joint, the sound translating device can be rotated about the axis of its nipple 46 so that suitable disposition of the conductors 36 can be made with a minimum of inconvenience to the wearer.

Various materials can be used for producing the members 20 and 26, among which various synthetic resins and plastics have been found to be eminently satisfactory from the standpoint of weight, appearance, comfort, and workability. The earpiece thus described, is primarily intended for use with one ear only, in the case described, the right ear, and for this reason, the articulated members have been shown as relatively offset in their entireties. It will be evident to those skilled in the art that a mere reversal of relative posi-

tions of the various parts would produce an earpiece especially applicable to the left ear of a user.

Inasmuch as commercial requirements render it desirable that a device be as universally applicable as possible, an earpiece has been depicted in Figs. 6 to 9 inclusive, intended for application to either a right or left ear by merely shifting the sound source or sound translating device from one surface of the depending member to the other. In this modification, the supporting member 50 has its forward end pivotally articulated with respect to the depending member 52 by means of a rivet 28 or the like together with the bearing washers 30 and a resilient washer 32 as in the case of the preceding example. Near its forward and upper end however, the supporting member 50 is offset to provide a connecting portion 54 in a plane parallel to but displaced from its major surfaces. Similarly, the depending member 52 provides a connecting portion 56 whose surfaces are parallel to but displaced from its major surfaces. By virtue of this displaced relationship of the cooperating connecting portions, the major surfaces of the articulated members will be symmetrically disposed with regard to a common medial plane as viewed in plan in Fig. 9. This disposition of the members renders the device equally suited for use with either ear, particularly since the internal groove 42 of the mounting ring 40 is centrally disposed with respect to the ring whereby the resilient annulus 44 will engage the grooved nipple 46 and retain it in assembled relationship with the earpiece upon insertion from either surface of the depending member 52.

Since Fig. 2 depicts the general relationship with the human ear assumed by either form of the device described, it will be noted that the articulated portions of the members will lie forwardly of the pinna, the mounting ring and consequently the sound source will lie adjacent the concha and the enlarged lower end 53 of the supporting member will assume a position posterior with respect to the lobe 60 of the ear.

Where the material constituting the articulated members possesses yieldability and/or resilience, the device will conform somewhat better to some types of ear structures, which are known to vary considerably.

Under many circumstances, two such earpieces will be used simultaneously by an operator, one supported at each ear. In this event, the several conductors can be connected electrically and physically in a manner to provide the most convenience to the user.

Whereas only two modifications of the invention have been described with reference to the drawings, various alternative constructions will suggest themselves to those skilled in the art just as they have been recognized already by the present inventor, and accordingly, the scope of this invention should not be restricted beyond the substance of the appended claims.

I claim:

1. An earpiece comprising a plurality of articulated members, pivot means adjustably relating said members for engagement of opposite surfaces of the pinna of the human ear, one of said members providing means for attachment of a sound source.

2. An earpiece comprising two members adjustably related for engagement of opposite surfaces of the pinna of the human ear, pivot means articulating said members forwardly of said

pinna, one of said members providing means for attachment of a sound source.

3. An earpiece comprising a plurality of articulated members, pivot means adjustably relating said members for engagement of opposite surfaces of the pinna of the human ear, and yieldable means maintaining said members in an adjusted relationship, one of said members providing means for attachment of a sound source.

4. An earpiece comprising a plurality of articulated members, pivot means adjustably relating said members for engagement of opposite surfaces of the pinna of the human ear, and a resilient socket carried by one of said members for attachment of a sound translating device.

5. An earpiece comprising two articulated members, pivot means adjustably relating said members for engagement of opposite surfaces of the pinna of the human ear, and means for attaching a sound translating device rotatably to either surface of one of said members.

6. An earpiece comprising a plurality of articulated members, pivot means adjustably relating said members for engagement of opposite surfaces of the pinna of the human ear, one of said members having a depending end spaced from said pivot means by a distance substantially equal to that between the pinna and concha of an average human ear providing means for attachment of a sound source, said end being adjustable with respect to said pivot means to a position overlying the concha of the average human ear.

7. An earpiece comprising a plurality of articulated members, pivot means adjustably relating said members for engagement of opposite surfaces of the pinna of the human ear, and fastening means accessible from opposed surfaces of one of said members for attachment of a sound source at either of said surfaces.

8. An earpiece comprising a plurality of articulated members, pivot means adjustably relating said members for engagement of opposite surfaces of the pinna of the human ear, and a recessed resilient ring carried by one of said members providing yieldable means for attachment and detachment of a sound source.

9. An earpiece comprising a support; said support having a suspending portion for engagement behind the pinna of either human ear and having a portion depending from said suspending portion for locating a receiver adjacent the outer surface of either ear; fastening means carried by said depending portion; and a receiver providing complementary fastening means releasably and reversibly interengageable with the first said fastening means whereby said earpiece is applicable to either a right or left ear, one of said fastening means including a socket providing a resilient detent, the other of said fastening means including a plug containing a recess for reception of said detent.
